SIGNAL HORN

Clyde C. Farmer, Pittsburgh, Pa., assignor to
The Westinghouse Air Brake Company, Wil-
merding, Pa., a corporation of Pennsylvania

Application October 24, 1936, Serial No. 107,391

4 Claims. Cl. 177—7

This invention relates to signal devices and more particularly to the type adapted to be operated by fluid under pressure or the like.

On locomotives employed in railway service, the fluid pressure operated signal devices are usually mounted with the mouth or open end of the horn pointed towards the front end of the locomotive and this permits foreign matter to enter the horn which is liable to cause the device to fail to operate. This condition is particularly true in winter when sleet and snow are driven into the open end of the horn and either accumulates in the horn bell or reaches a vital portion such as the valve mechanism located at the base of the sound tube. Foreign matter such as insects may also enter and become lodged in the horn or valve mechanism located at the base thereof, and one object of the invention is to provide a signal device in which the above difficulty is obviated.

With signal devices mounted as above described, the signal produced thereby is projected forwardly from the locomotive and it is therefore difficult for trainmen, such as a flagman, at the rear end of a long train to hear such signal and another object of the invention is to provide a signal device so constructed as to facilitate the hearing of the signal at the rear of the train.

These objects are accomplished by providing a signal device which is swiveled upon a mounting base and which is arranged to normally point toward the rear of the locomotive so as to be protected from foreign matter and in which position it may be operated to signal trainmen at the rear of a train. When it is desired to project a signal forwardly from the locomotive, the signal device is first turned so as to point forwardly and it is then operated to produce the desired signal. When the signal is completed, the signal device is then automatically returned to its normal position with the horn pointing toward the rear of the train.

Other objects and advantages will be apparent from the following more detailed description of the invention.

In the accompanying drawing: Fig. 1 is a dia-grammatic, sectional view, the section being taken on two different planes, of my improved signal device associated with means for controlling the operation thereof; and Figs. 2 and 3 are sectional views taken on the lines 2—2 and 3—3 in Fig. 1.

As shown in the drawing, the improved signal device comprises a sound producing device 1 carried by and swivelly mounted on a base member

or support 2 adapted to be secured to any suitable fixed portion 2A of a locomotive.

The sound producing device 1 may be of any desired construction adapted to be operated by fluid pressure. As shown in the drawing, for the purpose of illustration, the device 1 may comprise a valve portion 3 and a horn 4 associated therewith and having an open end or mouth 5 through which sound generated in the valve portion 3 is projected into space. The lowermost portion 6 of the interior wall of the horn is sloped downwardly towards the mouth 5 so as to provide drainage from the horn bell for any foreign matter which may perchance enter therein.

The base 2 is provided with an upwardly extending boss 7 having on its end a bearing face 8 disposed in a horizontal plane, while the sound producing device 1 is provided with a depending boss 9 having on its end a bearing face adapted to engage the face 8 on boss 7 and turn thereon.

A shroud 10 projects from the lower end of the boss 9 down over the boss 7 to keep foreign matter away from the bearing between the bosses 7 and 9, and a lug 11 projects horizontally from the exterior face of the shroud 10 and is adapted to engage two spaced resilient bumpers 12 and 13 secured to ears 14 and 15 projecting from the base 2. These bumpers are spaced to permit the sound producing device 1 to turn through 180 degrees, that is, from the position shown in the drawing in which the horn 4 is pointing toward the rear of a locomotive to a position in which said horn is pointing towards the front of a locomotive; the front and rear of the locomotive being indicated in the drawing by arrows and proper legends associated therewith.

A vertically disposed spindle 16 is mounted and adapted to turn in suitable bearings or guides provided in the base 2 at either side of a cavity 17 formed in said base. One end of the spindle 16 extends centrally through the face 8 of boss 7 and into the depending boss 9 of the sound producing device 1 wherein said spindle is secured to said device in any suitable manner, such as by screw threaded engagement, whereby turning of the spindle will turn the sound producing device 1 on the boss 7.

A gear 18 disposed in chamber 17 is secured to the spindle 16 by any desired means such as a key (not shown). A rack 19 having teeth 20 adapted to engage the teeth 21 of the gear 18 is disposed at one side of the spindle 16 and is slidably mounted in suitably spaced bearings or guides 22, 23 provided in the base 2. One end

of the rack 19 extends into a chamber 24 and is reduced in cross-section to form a pin like projection 25 upon which there is mounted a spring seat in the form of a washer 26. A spring 27 in the chamber 24 has one end engaging the washer 26, while the other end engages a cover 28 secured to the base 2 over the open end of chamber 24.

A flexible diaphragm 29 is clamped around its 10 periphery between a flange 30 on the base 2 and a flange 31 provided on a cover 32 which is secured to the base 2, and said diaphragm is secured at its center to the left hand end of the rack 19 between a follower plate 33 at one side 15 and a clamping plate 34 at the opposite side. The left hand end portion of the rack is of reduced cross-section to provide a shoulder which the follower plate 33 engages, and to provide a stud 35 which extends through suitable apertures 20 provided centrally through the plates 33 and 34 and diaphragm 29. A nut 36 is provided on the end of the rack for pressing the plate 34 against one side of the diaphragm and the other side of said diaphragm against the follower plate 33.

25 A chamber 37 is formed at the right hand side of the diaphragm 29 and is in permanent communication with the atmosphere through a breather port 38, while a chamber 39 is formed at the left hand side of the diaphragm and is open 30 to a pipe 40 which leads to a magnet valve device adapted at one time to supply fluid under pressure to chamber 39 and at another time to vent fluid under pressure from said chamber.

35 This magnet valve device comprises a magnet 41 and oppositely seating valves 42 and 43 controlled thereby, each of said valves having a fluted stem slidably mounted in suitable bores in the device in axial alignment with each other and engaging in a chamber 44 to which the pipe 40 is connected. The valve 42 is contained in a chamber 45 which is open to the atmosphere through a passage 88 and is adapted to control communication between said chamber and chamber 44. The valve 43 is contained in a chamber 46 which is connected to a pipe 47 leading to any suitable source of fluid under pressure such as may be provided in a reservoir 48 and is adapted to control communication from chamber 43 to chamber 44. A spring 49 in chamber 50 46 acts on the valve 43 for urging it to its seat, as shown in the drawing.

The mounting base 2 for the sound producing device 1 has a chamber 50 into which projects a portion 52 of a fluid pressure supply valve device 51. The lower end of the spindle 16 projects through a suitable bore in the portion 52 and is provided with an annular collar 53 between which and the upper surface of said portion there is provided a ring washer 54 preferably disposed in an annular cavity in the collar 53. This washer is provided primarily for effecting a leak proof seal between the collar 53 and portion 52 and for this purpose may be 60 made of a resilient material such as rubber. However, if desired, this washer may be made of any suitable bearing material such as babbitt and act as the support for the spindle 16 and sound producing element 1 instead of the boss 7, it 65 being evident that such bearing material would also act to provide a leak proof seal.

The lower end of the spindle 16 extends below the portion 52 of the valve device 51, and secured to said end is a cap nut 55 between which 75 and the lower face of portion 52 is disposed a

ring sealing washer 56 preferably disposed in an annular cavity in the face of the nut.

A passage 57 is provided in the sound producing device 1 through which fluid under pressure is adapted to be supplied to valve mechanism 3 of said device for operating same to produce a signal. This passage is connected to an axial bore 58 which extends through the spindle 16, the lower end of the bore being closed by the cap nut 55.

A substantially semi-circular cavity 59 is provided in the extended portion 52 of the valve device 51 around and open at one side to the spindle 16, and a port 60 is provided through the wall of said spindle connecting said cavity to the bore 58 and this port is so located as to be disconnected from said cavity as the spindle is turned substantially from the position shown through 180 degrees to its other position, as will be later described.

20 The valve device 51 comprises a valve piston 61 having at one side a chamber 62 and at the opposite side a chamber 63 connected by a passage 64 to the fluid pressure supply pipe 47. A valve 65 is contained in the chamber 63 for controlling communication from said chamber to a passage 66 leading to cavity 59 and this valve is secured to the valve piston 61 so as to move therewith. A spring 67 is provided in chamber 62 and acts on the valve piston 61 for urging the valve 65 to its seated position.

25 The chamber 62 is connected to a pipe 68 which leads to a magnet valve device comprising a magnet 69 and a double beat valve 70 controlled thereby. The valve 70 is contained in a chamber 71 to which the pipe 68 is connected and is adapted to control communication between said chamber and a chamber 72 which is connected to the fluid pressure supply pipe 47 and another chamber 73 which is open to the atmosphere through a passage 74. A spring 75 is provided in chamber 72 for urging the valve 70 to the position shown in the drawing.

30 A manually controlled switch device adapted to be operated by the engineer on the locomotive is provided for controlling the operation of the magnets 41 and 69. This switch device comprises a flexible contactor 77 and three flexible contact fingers 78, 79 and 80 secured in spaced relation in a block 76 for any suitable insulating material. The contactor 77 is provided with an operating handle 85 preferably made of insulating material and is connected to a wire 81 which leads to one terminal of any suitable source of electrical energy such as provided by a battery 82, the other terminal of which is grounded. The fingers 78 and 80 are both connected to a wire 83 leading to one terminal of magnet 69 the other terminal of which is connected to ground, while the finger 79 is connected to a wire 84 leading to one terminal of magnet 41 the other terminal of which is grounded.

35 The switch device is shown with the contactor 77 and fingers 78 to 80 in their normal positions, in which the circuits to magnets 41 and 69 are open and said magnets therefore de-energized.

40 With magnet 41 deenergized, spring 49 acts to seat valve 43 and unseat valve 42 which vents the diaphragm chamber 39 to the atmosphere through pipe 40, chambers 44 and 45 and atmospheric passage 88. This permits spring 27 acting on the right hand end of the gear rack 19 to hold said rack and thereby the gear 21, 75

spindle 16 and sound producing device 1 in their normal position as defined by the engagement of stop 11 on the shroud 10 with the rubber bumper 12. In this position the open end 5 of the horn 4 is pointed toward the rear of the locomotive.

Fluid under pressure is supplied to the reservoir 48 in any suitable manner. From reservoir 48 fluid under pressure is supplied through pipe 47 to chamber 46 in magnet 41, chamber 72 in magnet 69 and to chamber 63 in the valve device 51. With the magnet 69 deenergized, the spring 75 holds the double beat valve 70 in the position shown in the drawing in which fluid under pressure flows from chamber 72 to chamber 71 and thence through pipe 68 to chamber 62 in the valve device 51. The fluid pressures in chambers 62 and 63 at the opposite sides of the valve piston 61 thus are equalized which permits spring 67 to urge the valve piston 61 to the position shown in the drawing and thereby urge the valve 65 into engagement with its seat.

If the engineer on the locomotive at the head end of a train desires to sound a warning at a grade crossing or the like, where it is desired that the signal shall be directed toward the forward end of the train, he operates the switch handle 85 to flex the contactor 77 towards the left hand engaging first the finger 79 and then further movement flexes finger 79 into engagement with finger 78. Electric current supplied from battery 82 to contactor 77 is thereby supplied to fingers 79 and 78 and thence through wires 84 and 83 to magnets 41 and 69 respectively, whereupon said magnets become energized.

Energization of magnet 41 seats valve 42 and unseats valve 43 which permits fluid under pressure to flow from the fluid pressure supply pipe 40 47 and chamber 46 to chamber 44 and thence through pipe 40 to diaphragm chamber 39. The pressure of fluid thus obtained on the diaphragm 29 flexes same and moves the rack 19 towards the right hand compressing spring 27. This movement of the rack 19 turns the gear 21 and thereby the spindle 16 and sound producing device 1 secured thereto in a direction indicated by the arrow on Fig. 3 from the position shown in the drawing through an arc of 180 degrees to a diametrically opposite position defined by engagement of the stop 11 with the resilient bumper 13. The horn 4 is now positioned to project sound forwardly from the locomotive.

The energization of magnet 69 acts to seat the double beat valve 70 in its lowermost position closing communication from chamber 72 to chamber 71 and opening communication from chamber 71 to chamber 73 whereupon fluid under pressure in chamber 62 at the spring side of valve piston 61 is vented to the atmosphere through chambers 71 and 73 and atmospheric passage 74.

This venting of fluid under pressure from chamber 62 permits the pressure of fluid in chamber 63 to move the valve piston 61 towards the right hand and thereby unseat the valve 65 which permits fluid under pressure to flow from the supply pipe 47 and connected chamber 63 to passage 66 and thence to the semicircular cavity 59. With the sound producing device 1 and spindle 16 turned 180 degrees from the position shown in the drawing, the port 60 in said spindle is open to cavity 59 at the left hand end thereof, as viewed in Fig. 3 of the drawing, so that fluid under pressure supplied to said cavity

flows through said port to bore 58 in the spindle 16 and thence through passage 57 in the sound producing device 1 to the valve mechanism 3 thereof, for effecting its operation to produce a signal which is projected through the horn 4 to space forward of the locomotive.

After the desired signal has been effected, the contactor 77 is permitted to move back to its normal position in which the contact fingers 78 and 79 are disconnected therefrom thereby opening the circuits through magnets 41 and 69 which consequently become deenergized.

The deenergization of magnet 69 permits spring 75 to seat the double beat valve 70 in its upper position so that the fluid pressures again equalize in chambers 62 and 63 at the opposite sides of valve piston 61 whereupon spring 67 shifts said valve piston to the position for seating valve 65 which cuts off the supply of fluid under pressure to the sound producing device 1 so that said device ceases to operate.

The deenergization of magnet 41 permits spring 49 to seat valve 43 and unseat valve 42 which vents fluid under pressure from the diaphragm chamber 39 to the atmosphere. The pressure of spring 27 then moves the rack 19 and thereby operates the gear 21 to return the spindle 16 and sound producing element 1 to its normal position, as shown in the drawing, in which the horn 4 points toward the rear of the train.

If when the sound producing device 1 is pointed toward the front of the train it is desired to project a series of blasts forwardly from the locomotive, the contactor is operated as above described to effect the initial blast. It is then released only sufficiently to permit the contact finger 79 to flex away from the contact finger 78, thereby causing deenergization of magnet 69 but retaining the magnet 41 energized.

By holding the magnet 41 energized the sound producing device 1 is maintained in the position pointing forwardly from the locomotive, while the deenergization of magnet 69 permits spring 67 to operate the valve piston 61 to seat the valve 65 and thus cause operation of the sound producing device 1 to cease. Then when it is desired to project another blast or signal from the sound producing device 1, the contactor is again operated to flex finger 79 into engagement with finger 78. The magnet 69 is thereby again energized and acts to supply fluid under pressure to the sound producing device 1 for operating same. By thus operating the switch device to hold the magnet 41 energized and to alternately energize and deenergize the magnet 69, any desired series of signal blasts may be projected from the sound producing device 1 forwardly from the locomotive. After the desired signal has been effected, then the contactor 77 is permitted to flex back to its original position, as shown in the drawing, in which both magnets 69 and 41 are deenergized. The sound producing device 1 then ceases to operate and is returned to its normal position, as above described.

As the sound producing device 1 is turned from its normal position to the position for projecting a signal forwardly from the locomotive, it will be noted that the port 60 in spindle 16 is lapped by the portion 52 of the valve device 51 until said device substantially attains the position pointing toward the front of the locomotive, at which time said port opens to the left hand end of cavity 59, as viewed in Fig. 3. This is desirable in order to prevent fluid supplied to cavity 59 upon ener-

gization of magnet 69 from flowing to bore 58 in the spindle 16 and thence to the sound producing device and operating same before said device becomes substantially positioned to project the signal forwardly from the locomotive as desired. In other words, it would be substantially useless and undesirable to have the sound producing device operating while being turned to the position for projecting the signal forwardly 10 from the locomotive, and this is prevented by lapping the port 60, as above described.

When it is desired to project a signal rearwardly from the locomotive to a flagman or the like at the rear of a train, the contactor 77 is flexed toward the right hand into engagement with contact finger 80, thereby energizing the magnet 69. The magnet 41 remains deenergized upon this operation of the contactor 77, as will be evident, so that the sound producing device 1 20 remains in the position pointing toward the rear of the locomotive. The energization of magnet 69, however, causes the valve piston 61 to unseat the valve 65 and supply fluid under pressure to cavity 59 as hereinbefore described, and thence 25 through port 60, which is open to said cavity at the right hand end thereof, as viewed in Fig. 3 of the drawing, to bore 58 leading to the sound producing device 1 for effecting operation thereof to project a signal toward the rear of the train. By moving the contactor into and out of 30 engagement with contact finger 80, the valve piston 61 may be caused to alternately open and close the valve 65 and thereby operate the sound producing device 1 to effect whatever signal is 35 desired, as will be evident.

It will now be evident, that since the sound producing device 1 is normally carried with the open end of the horn 4 pointing toward the rear of the locomotive, the horn is protected 40 against entry of foreign matter which would be liable to cause failure thereof, and since the horn is rotatable upon its base from a position pointing toward the rear of the locomotive to a position pointing toward the front of the locomotive, signals may be projected in either direction. 45

While one illustrative embodiment of the invention has been described in detail, it is not my intention to limit its scope to that embodiment 50 or otherwise than by the terms of the appended claims.

Having now described my invention, what I claim as new and desire to secure by Letters Patent, is:

55 1. In combination, a base member, a spindle rotatably mounted in said base member, a fluid

pressure operated sound producing device secured to said spindle and rotatable therewith, means for rotating said spindle and thereby said device from one position to another position, said spindle having an axial passage through which fluid under pressure is adapted to be supplied to said device for effecting operation thereof to produce sound and also having a radial port open at one end to said passage, said base member having a fluid pressure supply passage open to the other end of said port in said positions for thereby supplying fluid under pressure to said axial passage, rotation of said spindle relative to said base member between said positions being adapted to close communication between said 15 passage and port.

2. In combination, a sound producing device rotatable to either one or the other of two fixed positions, mechanism for turning said device to said positions, means for effecting operation of said device to produce sound, a member movable in either one direction or another direction, and mechanism operative upon movement of said member in said one direction to effect operation of said means, and operative upon movement of 20 said member in the other direction to effect operation of both said mechanism and means, and means for preventing operation of said device to produce sound while said device is turning between said positions. 30

3. In combination, a sound producing device rotatable to either one or the other of two fixed positions, mechanism for turning said device to said positions, means for effecting operation of said device to produce sound, a member movable 35 in either one or another direction, and mechanism operative upon movement of said member in the one direction to effect operation of said means and in the other direction to effect operation first of said turning mechanism and then of the 40 means.

4. In a signal horn device, in combination, a base member, a spindle rotatably mounted in said base member, a sound producing device carried by said spindle and operable by fluid under pressure to produce sound, said spindle being provided with a passageway through which fluid under pressure is supplied to said sound producing device, means for effecting the rotation of said spindle, and means for controlling communication through said passageway and operative in two positions of said spindle to open said communication and adapted to close said communication in the rotation of said spindle between said positions. 50

55 CLYDE C. FARMER.
